UNITED STATES PATENT OFFICE

101,078

DESIGN FOR A MAY BASKET

Stella Wilson, Omaha, Nebr.

Application June 26, 1936, Serial No. 63,520

Term of patent 14 years

To all whom it may concern:

Be it known that I, Stella Wilson, a citizen of the United States, residing at Omaha, in the county of Douglas and State of Nebraska, have invented a new, original, and ornamental Design for a May Basket, of which the following is a specification, reference being had to the accompanying drawing, forming part thereof.

Fig. 1 is a side elevation of a may basket showing my new design.

Fig. 2 is an upper end view.

I claim:

The ornamental design for a may basket, as shown.

STELLA WILSON.
